UNITED STATES PATENT OFFICE.

HARRY FRANK AND JOHN LEWIS, OF FORK RIDGE, TENNESSEE.

MINE-DOOR-OPERATING APPARATUS.

Application filed April 13, 1922. Serial No. 552,119.

To all whom it may concern:

Be it known that we, HARRY FRANK and JOHN LEWIS, citizens of the United States, residing at Fork Ridge, in the county of Claiborne and State of Tennessee, have invented certain new and useful Improvements in Mine-Door-Operating Apparatus, of which the following is a specification.

Our invention relates to improvements in mine doors, for controlling the air currents in the mines.

An important object of the invention is to provide a mine door, which is automatically opened, and held in the open position, upon the approach of the train, and then closed as the train passes the same.

A further object of the invention is to provide car wheel completed circuits, and means operated thereby, to shift the door to the open and closed position, and lock it in the open position.

A further object of the invention is to provide means of the above mentioned character, which is comparatively simple in construction, automatic in operation, reliable, strong and durable.

Other objects and advantages of the invention will be apparent during the course of the following description.

In the accompanying drawings, forming a part of this specification, and in which like numerals are employed to designate like parts throughout the same,

Fig. 1 is a side elevation of a mine door embodying our invention, the casing containing the operating means being shown in section,

Fig. 2 is a plan view of a section of the track showing the door in horizontal section.

Fig. 3 is an enlarged detail section on line 3—3 of Fig. 7, showing a wheel engaging the rail and ramp or contact plate,

Fig. 4 is an enlarged side elevation of a switch which controls the operation of the motor,

Fig. 5 is a detail section through one end of the gate, showing the construction of the hinge, the same being taken on line 5—5 of Fig. 4,

Fig. 6 is a horizontal section taken on line 6—6 of Fig. 1,

Fig. 7 is a diagrammatic view of the circuit,

Fig. 8 is an enlarged central vertical section through the driving means or gearing of the gate, parts in elevation,

Fig. 9 is a detail section taken on line 9—9 of Fig. 8, parts in elevation,

Fig. 10 is a plan view of a stripped beveled gear, and,

Fig. 11 is a perspective view of one of the track contact plates.

In the drawings, wherein for the purpose of illustration is shown a preferred embodiment of our invention, the numeral 15 designates a door frame, as a whole, arranged at the entrance end of the mine shaft or passage. This frame may embody a horizontal beam 16 to which are secured vertical beams 17. The track rails 19 preferably pass over the horizontal beam 16, and we preferably provide fillers 20 and 21, above the beam 16 and upon opposite sides of the track rails 19 to prevent the passage of air currents, beneath the door, to be described.

Mounted within the door frame 15 are door sections 22, of any well known or preferred construction, which are adapted to swing outwardly to open position, as indicated by the arrow in Fig. 2. The door sections 22 are rigidly connected with vertical shafts 23. This connection is preferably affected by means of strips 24, secured to the door section by bolts or rivets 26, and these strips have jaws 27 and 28, rigidly connected with the shafts 23 by means of bolts 29 or the like. The shafts 23 have their upper ends suitably journaled in openings 30 in the upper channel beam 18, while their lower ends may be journaled in bearings 31, suitably secured within the channel beam 16.

Extending longitudinally of the door sections 22, within the beam 18, is a horizontal shaft 31', journaled in bearings 32, carried by brackets 33, which in turn are rigidly mounted upon the beam 18. Beveled gears 34 and 35 face in opposite directions and are rigidly mounted upon the horizontal shaft 31', outwardly of and adjacent to the bearings 32. These beveled gears engage beveled gears 36 and 37 respectively, which are rigidly mounted upon the upper ends of the vertical shaft 23.

As clearly shown in Figs. 1 and 9, the numeral 38 designates a motor, preferably suspended from the end of the beam 18, and arranged outwardly of and adjacent to one of the beams 17. This motor has an armature shaft 39, journaled in a bearing 40 carried by a depending bracket 41, which

is bolted to the beam 18. The armature shaft 39 carries a worm 41', at its outer end, which engages a worm wheel 42, Fig. 8. This worm wheel is rigidly mounted upon a sleeve 43, rotatable upon a support-shaft 44. The lower end of this support-shaft is rigidly mounted within the end of a horizontal bracket 45, which is bolted at 46, to the beam 17. The support shaft 44 extends upwardly vertically and is provided at its upper end with a tubular cross head 47, pivotally receiving the shaft 31'. The sleeve 43 is rotatable within openings 48, formed in the beam 18, and projects above this beam, and carries a beveled gear 49, rigidly mounted thereon. This beveled gear, Fig. 10, is stripped, being provided with a set of teeth 50, for one-eighth of its circumference.

The free right end of the shaft 31' is journaled in a bearing 51, carried by a bracket 52, which is rigidly bolted to the beam 18. Arranged between the bearing 51 and the right bearing 32 are beveled gears 53 and 54, having teeth throughout their periphery. These beveled gears have hubs 55, which are rigidly bolted or clamped to the shaft 31'. The beveled gears are positioned upon opposite sides of the tubular cross head 47, in close proximity thereto, to be engaged in succession, by the teeth 50 of the beveled gear 49. As these beveled gears 53 and 54 are arranged upon opposite sides of the beveled gear 49, they will of course serve to drive the shaft 31' in opposite directions, for a purpose to be described.

After the door sections 22 have been swung outwardly to the open position, means are provided to hold the same in such open position, including plates 56, preferably formed of iron, and bolted to the door sections 22. These plates are preferably insulated from the door section. The plates 56 are secured to the door sections, adjacent the vertical shafts 23, and are adapted, when the door sections are opened, to move in proximity to locking electromagnets 57, which are mounted upon brackets 58, rigidly mounted upon the vertical beams 17. It might be stated at this point that when the doors are swung to the open position, by the motor and associated elements, the circuit for driving the motor is opened, and the motor will stop, while the circuit for the electromagnets is closed, and these magnets energized and the plates 56 held adjacent the same.

Attention is now invited to Figs. 2 and 7, wherein track contacts or ramps 59 and 59' are shown, which are placed outwardly of and near the rails 19, and project upwardly beyond the same slightly, to contact with the periphery of the wheel 60 of the car or train, and thereby electrically connect the rail and the track contact. The track contact is of course thoroughly insulated from

the rail 19, and this may be affected by employing an insulating block 61, between the rail and track contact, and connecting the parts by a bolt 62, also insulated from the rail and the track contact. Of course the precise manner of connecting the track contacts with the rail, is immaterial, as the same may be varied. In Fig. 7, the track contacts are shown in side elevation, with the rail behind them. The track contact 59 has electrical connection with a wire 63, extending to the right, and connected with the track contact 59'. The numeral 64 designates a track contact, disposed inwardly of and suitably near the track contact 59, and insulated from the rail, in a similar manner, as described in connection with the track contact 59. The track contact 64 has electrical connection with a wire 65, and this wire extends to the right, and is electrically connected with a track contact 66, arranged suitably near the track 59, and insulated from the rail, and positioned with relation to the rail, as explained in connection with the track contact 59.

The numeral 67 designates a source of current, connected with a wire 68, connected with the rail 17. The opposite pole of this source of current is connected to a wire 69, connected with a wire 70, which may be a trolley wire. A wire 71 is connected with the wire 70, and has electrical connection with a metallic contact plate 72, Fig. 4, which contact plate is carried by a vertical arm 73, from which it is thoroughly insulated. The arm 73 is suitably mounted upon the beam 18. The contact plate 72 is adapted to be engaged and disengaged by a coacting contact arm 74, rigidly mounted upon a vertically swinging arm 75, pivoted at 76, upon a bracket 77. The contact arm 75 is swung to the left, Fig. 4, by a retractile coil spring 75', so that the contact arm 74 normally engages contact plate 72, but this electrical engagement is broken when the electromagnet 82 is energized, which electromagnet is adapted to overcome the action of the spring 75'.

The bracket 77 is mounted upon the arm 18, and thoroughly insulated therefrom. The bracket 77 has a binding post 78, having a wire 79 secured thereto, and this wire leads to one pole of the motor 38. The opposite pole of the motor is connected with a wire 80, which is connected with the wire 63. A wire 81 is connected with the wire 70, and has a pair of electromagnets 82 connected in series therewith, and these electromagnets serve to attract a plate or armature 83, which is rigidly mounted upon the vertically swinging arm 75, and thoroughly insulated therefrom, as clearly shown in Fig. 4. The electromagnets 82 are carried by a vertical arm or bracket 84, suitably mounted upon the beam 18. The wire 81 also has the lock 130

ing electromagnets 57 connected in series therewith, and the opposite end of the wire 81, is electrically connected with the wire 65.

The operation of the apparatus is as follows: With the mine doors closed, as shown in Fig. 2, and a train approaching the door sections 22, traveling from left to right, when the forward wheel 60 of the train engages the contact section 59, it will establish 10 electrical connection between the rail 19 and the track contact 59, thereby closing a circuit connected with the motor 38. This motor will now operate, and its armature shaft 39 will rotate the sleeve 43. This sleeve will 15 rotate the beveled gear 49, the teeth 50 of which are now positioned to engage the beveled gear 53, turning this beveled gear for substantially $\frac{1}{4}$ of a revolution. The shaft 31' will now be rotated in the direction of 20 its arrow, Fig. 8, and the vertical shafts 23 will be turned clockwise, and the door sections opened.

In the closed circuit for operating the motor 38, the current will flow from one pole 25 of the source of current 67, through wire 69, a portion of wire 70, wire 71, contact plate 72, contact 74, contact arm 75, wire 79, through the armature of the motor, wire 80, wire 63, track contact 59, wheel 60, rail 30 19, and through wire 68 back to the opposite pole of the source of current 67. By the time the motor has swung the door section to the opened position, a circuit is closed 35 for energizing the electric magnets 82 and 57, and this circuit is closed by the wheel 60 engaging the track contact 64, and electrically connecting the same with the rail 19. Of course the time that this second circuit will be closed will depend upon the 40 length of the track contacts 59, which may be properly calculated, depending upon the average speed at which the train will travel. In this second closed circuit, current will flow from one pole of the source of current 45 67 through wire 69, a portion of wire 70, a portion of wire 81, electromagnets 82, a portion of wire 81, electromagnets 57, a portion of wire 81, electromagnets 57, a portion of wire 65, contact 64, 50 wheels 60, rail 19, and wire 68, back to the opposite pole of the source of current 67. As soon as the circuit is thus closed, and the electromagnet 82 is energized, it draws 55 the arm 75 to the right, Fig. 4, breaking the electrical contact between the contact arm 74 and the plate 72. The circuit of the motor 38 is therefore opened, and the motor ceases to run. Simultaneously with this operation the locking electromagnets 57 are energized, and they attract the plates 60 56, thereby serving to hold the door sections 65 22 in the open position. By this means, when the train approaches the door sections, they will be automatically swung to the open position, and held until the train has passed

the same. When the train is passing through the door sections, its wheels continue to contact with the track contact 64, and also contact with track contact 66, thus tending to retain the electromagnet 82 energized. The 70 track contacts are constructed sufficiently long so that the rear wheel of each car of the train will contact therewith, before the front wheel disengages the same. By this means the circuit, including the electromagnet 82, when closed is retained continuously closed, during such period. The wheels of the train begin to engage the track contact 66 before they entirely disengage the track contact 64, and as soon as these wheels engage the track contact 66, the circuit for the electromagnet 82 is retained closed. In this closed circuit, the current will pass from one pole of the source of current 67 through wire 69, wire 70, a portion of the wire 81, electromagnets 82, a portion of wire 81, electromagnets 57, a portion of wire 81, electromagnets 57, a portion of wire 81, a portion of wire 65, track contact 66, wheels 60, rail 19, and wire 68, and back to the opposite 80 pole of the source of current. When the train has thus passed beyond the open door sections, its rear-most wheels disengage the track contact 66, and the spring 75' will at once swing the contact arm 74 into electrical connection with the contact plate 72. As soon as the wheels of the train engage the track contact 59', they will electrically connect it with the rail 19, and a circuit will be closed to drive the motor 38. In this 90 closed circuit, current will flow from one pole of the source of current 67, through wire 69, a part of the wire 70, wire 71, contact 72, contact arm 74, wire 79, motor 38, wire 80, a portion of the wire 63, track contact 59', rail 19, and through the wire 68, to the opposite pole of the source of current. This circuit will remain closed until the rear-most wheel of the train travels off of the track contact 59'. The closing of this circuit causes motor 38 to operate, and the sleeve 43 will be driven, and the beveled gear 49 will have its teeth 50 brought into engagement with the beveled gear 54, driving the shaft 31' in an opposite direction to its arrow, whereby the vertical shafts 23 are turned in an opposite direction to their arrows, and the door sections closed.

It is to be understood, that the form of our invention herewith shown and described, is to be taken as a preferred example of the same, and that various changes in the shape, size and arrangement of parts may be resorted to without departing from the spirit of our invention or the scope of the subjoined claims.

Having thus described our invention, we claim:

1. In apparatus of the character described, a track, a mine door extending across the

track and adapted to be shifted to opened and closed positions, electrical means to move the door to the opened position including a car wheel completed circuit closed at one point by the passage of a train, and electrical means including a car wheel completed circuit closed at another point by the passage of the train to open the first circuit and hold the door in the opened position.

10 2. In apparatus of the character described, a track, a movable door adapted to extend across the track, means to open the door, including a motor, a car wheel completed circuit connected with the motor and adapted 15 to be closed upon the passage of a train at a certain point on the track, a switch connected in the circuit, means adapted when energized to open the switch, electrical means adapted when energized to hold the 20 door in the open position, and a second car wheel completed circuit having the first and second named electrical means connected in series therewith, the second circuit being closed when the train approaches a certain 25 point in the track.

3. In apparatus of the character described, a track, a pair of horizontally swinging doors extending over the track, vertical shafts supporting the doors, gearing to turn the 30 shafts, a motor to drive the gearing, armature plates secured to the doors, electromagnets adapted to attract the armature plates when the doors are swung to the open position and the electromagnets are energized, a car wheel completed circuit connected with the motor, a switch connected in the circuit and adapted to open it, an electromagnet to actuate the switch, a second car wheel completed circuit having all of the 35 electromagnets connected therein, and a train to travel upon the track and close the 40 circuits, in succession.

4. In apparatus of the character described, a track including track rails, a pair of horizontally swinging door sections extending 45 across the track, upstanding shafts supporting the door sections, beveled gears secured to the upper ends of the shafts, a horizontal

shaft extended across the door sections, beveled gears carried by the horizontal shaft 50 and engaging the first named beveled gears, a pair of beveled gears rigidly mounted upon the horizontal shaft and facing in opposite directions and disposed in close relation, a stripped beveled gear arranged between said pair of beveled gears, a motor to drive the stripped beveled gear, and means to cause the motor to operate when a train traveling upon the track approaches the 60 door sections at a selected distance therefrom upon one side, and when the train passes through the door sections and reaches a selected point away from the door sections.

5. In apparatus of the character described, a track, a pair of swinging mine doors to extend across the track and adapted to be shifted to opened positions, means to swing the doors, a motor to drive such means, a source of current having one pole thereof connected with one rail of the track, a pair 70 of spaced contacts arranged near the track rail and insulated therefrom and adapted to be electrically connected with the rail by a wheel traveling upon the rail, a wire electrically connecting said contacts, a wire connecting the first named wire with one pole of the motor, a wire connecting the opposite pole of the motor and the opposite pole of the source of current, a switch connected in the last named wire, an electromagnet adapted when energized to open the switch, a pair of holding electromagnets arranged near the swinging doors, co-acting armature plates carried by the doors, a wire connected with one pole of the source of current 85 and having all of said magnets connected therein, a pair of spaced contacts arranged near the track rail and insulated therefrom and connected with the last named wire, the last named contacts being electrically connected with the rail by a wheel traveling upon the rail.

In testimony whereof we affix our signatures.

HARRY FRANK.
JOHN LEWIS.
